CLAIM

The ornamental design for the detail brush, as shown and described.

DESCRIPTION

FIG. 1 is a top, front perspective view of a detail brush according to the present disclosure;

FIG. 2 is a first side view of the detail brush of FIG. 1;

FIG. 3 is a front view of the detail brush of FIG. 1;

FIG. 4 is a second, opposite side view of the detail brush of FIG. 1;

FIG. 5 is a back view of the detail brush of FIG. 1;

FIG. 6 is a bottom view of the detail brush of FIG. 1; and,

FIG. 7 is a top view of the detail brush of FIG. 1.

The broken lines in the drawings illustrating environmental structure or boundaries that form no part of the claimed design.
